UNITED STATES PATENT OFFICE.

DAVID HYMAN, OF HARRISBURG, PENNSYLVANIA, ASSIGNOR OF ONE-HALF
TO JOSHUA W. JONES, OF SAME PLACE.

GLOBE-FRAME.

SPECIFICATION forming part of Letters Patent No. 411,443, dated September 24, 1889.

Application filed July 26, 1888. Serial No. 281,157. (No model.)

To all whom it may concern:

Be it known that I, DAVID HYMAN, a citizen of the United States, residing at Harrisburg, in the county of Dauphin and State of 5 Pennsylvania, have invented an Improvement in Globe-Frames, of which the following is a clear, full, and exact specification, which will enable skillful artizans to construct and use the same.

10 My invention relates to appliances adapted for electric lights, especially suited for use on electric-arc lights whether the same are hung in the open air, as in streets and parks, or in inclosed places in buildings, it being 15 applicable to almost all electric-light systems where globes are now used.

The object of my invention is to furnish a substitute for the globe now in use and which can be placed in a small and safe package, 20 and thus obviate to a great degree the objections that now exist against the shipment of globes. In making this substitute for globes several points must be taken in consideration to overcome many objections that would 25 be raised to its use. It is well known that any opaque body interposed between the light and the place to be illuminated will cast an intensely black shadow. To overcome this the sides of the lantern are made of sections of glass which abut against each other 30 at the edges, so that the corners will transmit light, which is not the case with lanterns having the edges of the sides sections joined together by metal strips, as is the case with 35 ordinary street gas-lamps. These sections are loosely held at top and bottom to permit of expansion due to the intense heat of the arc lamp and contraction which takes place when the light is put out. Another feature 40 is that the sides can be easily replaced by the ordinary street-light adjuster if one or more should be broken, whereas a globe if broken must be replaced by a new one. To hold the sections at top and bottom suitable top and 45 bottom pieces are used and are connected together by rods of very small diameter, which are located near the points where the edges of the glass meet, so that the reflection from the abutting edges will overcome the shadow 50 which would otherwise be cast by the rods. Moreover, the lantern may be with or with-

out bottom and may have one or more of its sides adapted as light-reflectors whether plain or curved and whether the sides are of glass or metal or of both kinds combined. 55

My preferred construction of lantern consists of a basal spider formed of a central hub and radial arms having grooved palms at the perimeter of the arms for retaining thereon the lantern-sides by holds therefor in said 60 grooves at the polygonal angles of the lantern, and having interior flanges on said arms for retaining thereon sections of the removable bottom of lantern, and the top of said frame is a sheet-metal disk formed with exterior lips bent down for embracing the lantern-sides exteriorly, and also formed with interior tangs struck from the said disk and bent down suitably for embracing said lantern-sides by bearing against their insides 70 adjustably, the central part of said disk having an aperture suitable to admit freely therethrough the rods of the electric-light supports. Vertical bolts connect said top plate with the palms near the perimeter of 75 said arms, the hub of said spider being secured to the light-holder by a jam-nut, setscrew, or other means, as the form of the holder may require. The mechanism for obtaining said objects is illustrated in the accompanying drawings, in which—

Figure 1 is an isometrical perspective view of my lantern detached from the holder. Fig. 2 represents a vertical section of the lantern-top, taken through the middle of the opposite 85 sides thereof; Fig. 3, the basal frame or spider at base of lantern in plan; Fig. 4, a cross-section of same, taken on the indicated line R R'; Fig. 5, a plan view of one of the similar sections of the lantern-bottom; Fig. 6, a cross-section of one of the radial arms of said bottom frame, taken at the line of the wire or pin, securing thereon the bottom sections; Fig. 7, a vertical section of my said lantern or globe frame, with an electric-arc light 90 illustrated in position therein. 95

Similar letters refer to similar parts throughout the several views and descriptions.

The spider or basal frame A' a' H consists of the hub H, in which is a socket K for attaching the spider to a part of the carbon-holder abutted thereto by set-screw or set-screws, 100

and of the diagonally-extended arms A, which have upon their outer ends the angular palms n', which latter are provided with the grooves n on top thereof between the ledges M and 5 palm n', and said arms are provided with inwardly-slanting flanges a', skirting them and the hub H alike, all being in form and location as shown in Figs. 1 and 6. The palm n' is shown wedged shape, and forms with the 10 raised part of the arms a recess or angle n² for one of the corners of the bottom glasses. Vertically above said basal frame is the correspondingly-angled top plate Q, provided with the downturned exterior flanges k, and 15 with the tangs G struck from the sheet that forms the top, and also turned down to stand parallel to and near the adjacent exterior flanges, as shown in Figs. 1 and 2. Said flanges are arranged to be parallel to the 20 ledges M on basal frame, and they bear alike against the glass faces or sides S in the corresponding vertical plane, and said tangs are arranged to bear against the insides of said faces of lantern yieldingly to compensate for 25 different thicknesses thereof. Said tangs may be bent back to the plane from which they were struck up, and thus allow the lantern-side to be removed without undoing the screw-bolts N, which latter are formed with thumb- 30 buttons above and with screw-threaded points below, and work in tapped holes T in the arms A, or may be provided with nuts below the arms A. The aperture P in the top plate, to admit therethrough the rods which support 35 the electric-light holder, affords approach to reach the sides S by the unaided hand when they are to be removed, as when cracked or broken. The grooves in said palms are amply deep and wide to admit therein, along with a 40 pane of glass, also a burnished or polished sheet of metal or metallic pane when said sides of lantern are to be converted into a reflector, as when the light would otherwise fall upon a blank wall. Said grooves n also admit 45 therein cuttings of sheet-rubber interposed between the palms and the basal margin or edges of the face S, to relieve the set of the latter on the basal frame and to prevent rattle by gusts of wind.

50 Upon the interior flanges a' on the arms A, hub H, and palm n' are supported the sections Z, preferably of glass, to form a transparent bottom of lantern. Said sections extend outwardly a little farther than the outer 55 side of the lantern-faces S, that the latter may bar the vertical displacement of said sections, yet permit their removal, when a cotter-pin C or a soft wire V, inserted through the opening in projection W of the arms A, and bearing 60 on said section of bottom, is also removed.

The lateral displacement of the sections Z is prevented by the arms A, against which their edges abut, and by the downward slanting of the ledges on the arms on which the 65 plates or sections Z are supported, thus gravitating toward the hub H of said basal frame. The ledges a' are a little lower than the

grooves n, and therefore the lower edges of the sides S may rest on said bottom sections; and said ledges being slanted centerward and downward, any particles from the spent carbons will be conveyed to and be collected about the hub H, thus preventing the emission of live particles from the lantern in houses, where safety is a requisite against fire. 70

In outdoor situations the bottom of lantern may be omitted where the destruction of insects may be desirable by admitting them directly to the fire of the light and when singed letting them drop out below. In many 80 instances, therefore, the lantern will not need to be removed, as the carbons may be replaced and adjusted by reaching them below through the opening of lantern-frame. 75

In Fig. 3 is shown the set-screw L on hub 85 of the basal frame, for attaching the hub to a shank of certain forms of holders that may be inserted in the eye K. In other cases or forms of holders said set-screw may be omitted, as a bottom nut, usually on said shank, 90 or other means may be utilized for attaching the lantern removably to the light-holders.

Although a rectangular form of lantern has been selected to illustrate my invention, it is clear that a hexagonal, octagonal, or other 95 polygonal form may be adopted by adopting the same principles of construction, it being necessary to vary the angles defining the grooves or supports of the sides and the corresponding flanges or tangs depending from the top plate. It is also clear that sections of cylinders may take the places of plane sides if the retaining-grooves be made semi-circular and the top-plate flanges be modified accordingly. In either form a portion of the 100 lantern side or sides may be converted into reflector-surface, where the brilliancy of light would not be desirable or where its benefit 105 would not be fully utilized.

I claim—

1. A lantern for arc electric lights, consisting of a basal frame or spider having central hub provided with an eye for attaching the lantern to the shank of the lower-carbon holder by a screw, said hub having radial 115 arms provided with grooves adapted to sustain therein the bottom edges of panes of glass, as the lantern-sides, a top plate having devices for securing the upper edges of the panes, and wire rods inserted through the top 120 plate and through the spider's arms, the wire rods having heads beneath and screw-nuts at upper end for connecting the plates squarely, all combined and arranged about the electric light, substantially as set forth. 125

2. In a lantern for arc lights, a basal frame having a central hub, a central eye K, and radial arms provided with flanges a', palms n', and recess n², in combination with the removable bottom sections Z, each adapted to rest 130 on the flanges a' and in recess n², substantially as described.

3. The skeleton globe-frame having the basal frame A' a' H as its support at corners

- thereof only, the sides S, retained at their basal edges in the grooves n independent of the bottom, the top plate Q, having the exterior flanges k, and the interior struck-up tangs 5 G, for resting on and embracing the lantern-sides, and the screw-bolts N, arranged in the corners inside of the glass sides, all combined and adapted substantially as and for the purposes shown and described.
- 10 4. The globe-frame consisting of the central hub having an eye and set-screw or set-screws L, and the radial arms A, provided with flanges a', slanting toward the center, and the grooved palms n' on their ends, the removable bottom 15 sections Z, constructed to rest upon the flanges a' and extending beyond the lantern sides and below the bottom of the grooves in the palms, the sides S, retained in the grooves n and securing the sections Z, the top plate Q, provided with parts for holding the sides in position, and the bolts N, for securing said top plate to said radial arms, substantially as described.
5. A globe-frame for electric-arc light, composed of rectangular panes of glass for the 20 sides of the said frame, a spider or bottom frame having a central hub adapted for at-

taching it to the metal carbon-holder, having radial arms extending from said hub to the sides, each formed at its extremity with a palm 30 having its upper side provided with grooves adapted for retaining therein the bases of said sides, said arms having also lateral flanges to hold thereon glass segments which form a transparent bottom, and a top frame constructed 35 to hold erect said sides, it having parts for bearing interiorly against the sides, and other parts for bearing against the sides exteriorly, and screw-bolts connecting said palms with said top frame, arranged inside near the intersection of the sides, substantially as shown and described.

6. The combination of an electric-light frame, a spider or bottom frame, the glass sides resting upon said spider or bottom frame, 45 and a top frame for securing the tops or upper ends of the glass sides and having an opening in the center for the electric-light frame which supports the spider or bottom frame, substantially as described.
